UNITED STATES PATENTS

2,669,048 2/1954 Easley et al. 134/107

ABSTRACT: An improved paddle arrangement for powderless etching machines for directing the etchant against the surface of a photoengraving plate. A plurality of paddle assemblies are located between the etching bath and the plate and are rotatable about parallel horizontal axes of a selectively variable speed. Each assembly includes a plurality of paddles having variously angled outer end portions. The relation of the paddle edge angles of each assembly in cooperation with those of the adjacent assemblies provides a uniform distribution and the equivalent effect of a substantially perpendicular direction of the etchant against the plate surface during rotation of the paddle assemblies at any speed within the normal operating range, thereby eliminating the need for the conventional baffles between the paddle assemblies.

PADDLE ARRANGEMENTS FOR POWDERLESS ETCHING MACHINES

The present invention relates generally to etching machines for etching photoengraving plates and relates more specifically to improvements in etching machines of the type employed for carrying out the Dow powderless process.

Etching machines of the general type to which the present invention is directed are shown for example in U.S. Pat. Nos. 2,669,048, 2,700,838 and 2,776,512. This type of machine is characterized by a tank adapted to contain a liquid etching bath which is maintained at a predetermined level, a cover for the tank beneath which the plate to be etched is supported face down in spaced parallel relation with the surface of the etching bath, means providing some type of planar motion of the plate, and means for directing etchant from the bath against the plate. As shown in the above-mentioned patents, the conventional means for directing etchant against the plate comprises a plurality of rotatable paddles provided with spaced vertical baffles therebetween, the paddles extending into the etching bath and in conjunction with the baffles directing a generally vertical stream of etchant against the plate face to effect the desired etching thereof.

It is well understood in the art that in order to prevent undercutting and bleeding of the photoengraving, the etchant must not be permitted to flow across the plate surface. Since the paddles are rotated at a relatively high speed, normally within a range of 300-1,000 r.p.m., the plate is accordingly subjected to a rapid succession of ribbons of etchant from the paddles. The paddle edge portions are conventionally angled at about 30° to provide an approximately vertical release of the etchant. However, since the speed of rotation of the paddles is variable, a single paddle angle cannot be relied on to give a vertical direction of etchant. At a higher speed the etchant is released earlier, and at a slower speed remains on the paddle for a later release. For this reason the conventional baffles are employed between the paddle assemblies and are carefully adjusted to direct the etchant substantially vertically against the plate.

The present invention eliminates the need for baffles by providing paddle assemblies in which the paddle edge portions are variously angled in a predetermined relation. In a preferred embodiment, each assembly includes a pair of diametrically opposed blades, one having an edge portion angled at 30°, the other having an edge portion angled at 60°. In operation, the angular release of etchant from the perpendicular by the 30° paddle is offset by the release from the 60° paddle of the adjacent assembly. Although the release angles will vary somewhat with speed change, the offsetting effect of the adjacent angled paddles will prevent the development of etchant flow across the plate surface and provide the equivalent effect of a substantially perpendicular direction of the etchant against the plate surface.

With the present invention, the expense of installing and adjusting the baffles is completely eliminated. Furthermore, the absence of the baffles permits a more thorough mixing of the etching bath and hence a higher quality etching of the plate. In a process which is already complicated by a large number of critical variables, the elimination of the baffles simplifies the process by removing a mechanical element which required careful adjustment. The baffles in addition due to their environmental location between the paddle assemblies attract contaminants in the form of concentrated etchant additives which can have a deleterious effect on the etching process.

It is accordingly a first object of the present invention to provide an improved paddle arrangement for powderless etching machines which provides a uniform distribution of etchant against a photoengraving plate surface over the normal operating speed range of the machine.

A further object of the invention is to provide the improvement as described which effectively eliminates the need for baffles between the paddle assemblies.

Another object of the invention is to provide the improvement as described which may be easily and economically fabricated and which may readily be adapted to convert conventional etching equipment.

Additional objects and advantages of the invention will be more readily apparent from the following detailed description of embodiments thereof when taken together with the accompanying drawings in which:

5 FIG. 1 is a front elevational view of an etching machine incorporating the present invention with a portion thereof broken away to show the interior arrangement of the machine;

10 FIG. 2 is an enlarged view of the rectangular area of FIG. 1 enclosed in broken lines schematically showing the etchant directing action of the paddle assemblies at a particular speed of rotation;

15 FIG. 2a is a view similar to FIG. 2 schematically showing the action of the paddles at a higher speed of rotation;

15 FIG. 3 is an enlarged end view partly in section of one of the paddle assemblies showing the configuration of the paddles carried thereon;

15 FIG. 4 is a side view of the paddle assembly shown in FIG. 3;

20 FIG. 5 is an end view partly in section showing a modified form of paddle assembly; and

20 FIG. 6 is an end view partly in section showing a further modified form of paddle assembly.

Referring to the drawings and particularly FIG. 1 thereof, an etching machine generally designated 10 is illustrated of a type adapted for carrying out a powderless etching process 25 and includes a frame 12 supporting a tank 14 adapted to contain an etching bath 16 which is maintained at a level 18. A tank cover 20 is pivotally mounted on cover supports 22 in a conventional manner permitting the cover to be opened fully when the machine is not in operation.

30 A plate support member 24 having clamps 26 adjustably attached thereto for securing a photoengraving plate 28 therebeneath is rotatably supported beneath the cover on shaft 30 which extends through the cover into the plate drive mechanism within the housing 32. This mechanism is of a conventional type and may impart either a rotational or a planetary motion to the plate 28 in the plane of the plate during operation of the machine.

35 A plurality of paddle assemblies 34 are located within the tank 14 between the etching bath and the plate 28. The assemblies 34 include paddle shafts 36 which are arranged in uniformly spaced parallel horizontal relation. Mounted on each paddle shaft 36 are a pair of paddles 38, the outer end portions of which upon rotation of the paddle shafts pass through the etching bath and serve to direct the etchant onto the downwardly facing surface of the photoengraving plate. The paddle shafts 36 which are journaled at each end by bearings (not shown) on the outer walls of the tank, are driven in rotation by the motor drive unit 40 mounted on the frame 50 12 below the tank by means of a plurality of drive belts 42 which pass around a drive sheave 44, idler sheaves 46 and similar sheaves on the ends of the paddle shafts. By means of this conventional drive arrangement, the paddle shafts are all driven in the same direction at the same speed. Suitable motor 55 control means (not shown) are provided to permit a selective variation of the speed of rotation of the paddle assemblies, and a normal range of operation might for example be 300-1,000 r.p.m.

60 The machine 10 as described thus far is of a conventional construction and the described elements and their functions are similar to the corresponding elements of the patents referred to above. The operation of the present machine is generally similar to those of the prior art in the sense that the etchant is driven by the paddle assemblies against the surface 65 of the photoengraving plate mounted in spaced relation above the etching bath, the plate being moved in a circular or other motion in its plane to insure uniformity of the etching action.

65 The novelty of the present invention is in the paddle assemblies and specifically in the angular relationship of the paddle 70 edge portions of each assembly. The angling of the outer edge of a paddle will determine the angular direction in which the etchant picked up by the paddle is released at a given speed of rotation of the paddle. For a given speed of operation, it is possible to select a paddle angle which will produce a substantially vertical direction of release of the etchant. The etchant

will, of course, tend to spread out upon release into a fan-shaped spray which will impact on the photoengraving plate in a zone of substantial width. Accordingly it is the average direction which is referred to in the present discussion.

Although a substantially vertical release direction could be obtained for a given speed, only an area of narrow width directly above the paddle at the time of release would receive the desirable truly perpendicular etchant delivery. Since the etching action is dependent on the impacting of the etchant against the plate, a deeper etch will result directly above the paddle even if it were possible to obtain an average vertical release direction.

Etching machines of this type, however, must be operable over a relatively wide speed range. Accordingly, if a given paddle angle were found suitable for one speed to direct the etchant in a substantially vertical direction, at a faster or slower speed the release would be at an earlier or later time and the angle of release would be changed accordingly. Conventional machines are thus provided with vertical baffle plates between the paddle assemblies, and a uniform paddle edge angle, for example 30°, is utilized to lift the etchant toward the plate. The use of baffles does not, however, eliminate the problem of uneven etching action since the most effective etching action occurs directly above the baffles.

In the present invention, it is possible to eliminate the conventional baffles due to the employment of a specific angular relationship of the paddle edges of each paddle assembly which in cooperation with the same relationships of the paddle edges of the adjoining assemblies produces a resultant delivery of etchant against the photoengraving plate having the equivalent effect of a substantially perpendicular direction of etchant against the plate surface over the normal operating speed range of the machine. Referring to FIGS. 3 and 4, the preferred paddle assembly construction includes a pair of paddles 50 and 52 formed of sheet metal and mounted on the paddle shaft 36 in substantially diametrically opposed relation by the bolts 54 extending therethrough. The manner of attachment of the paddles to the shaft is not of importance and the blades may alternately be welded or otherwise secured to the shaft.

The paddles each include a substantially radially extending portion 50a and 52a and an angled outer end edge portion 50b and 52b. As illustrated, the edge portion 50b is angled at 30° to the radially extending portion 50a, while the edge portion 52b is angled at 60° to the radially extending portion 52a.

In operation, the present paddle arrangement functions in the manner schematically indicated in FIGS. 2 and 2a. In FIG. 2, the paddle assemblies are depicted as rotating at a moderate speed and the cooperation function of the variously angled paddles is indicated by the broken line zones of etchant delivery A and B respectively for paddles 50 and 52. It will be noted that zones A and B overlap substantially in the regions C in which the etchant is delivered at opposing angles from the adjoining paddle assemblies. Any tendency for etchant flow to develop along the plate is stopped by the counteracting flow forces in the regions C. In addition the counteracting flow in the regions C enhances the etching action which otherwise would be least effective in these regions due to their distance from the delivery points of the paddles.

At a higher speed illustrated schematically in FIG. 2a, the zones produced by the paddles 50 and 52 are shifted somewhat to the left as shown at A' and B' but the regions C' of overlap are present and provide the same flow curbing function. It may thus be understood that the tendency of a 30° paddle of one assembly to induce a flow of etchant along a plate is counteracted by the tendency of a 60° paddle of the adjoining assembly to induce a flow in the opposite direction.

Experiments utilizing a glass topped machine were carried out utilizing all 30° paddles without baffles and a visibly apparent flow of etchant in one direction across the plate could be observed. Using all 60° paddles, a similar flow in the opposite direction resulted. With the present combination of 30° and 60° paddles, no perceptible flow could be detected. The

quality of photoengravings processed with the present paddle arrangement has been excellent.

Although the paddle assemblies should all rotate in the same direction, the direction itself is unimportant. Similarly, due to the high paddle speed, it is not necessary that the paddle assemblies operate with the uniform paddle alignment shown in the drawings. Belt slippage will in fact produce a random orientation of the assemblies.

In FIG. 5 a modified form of the preferred paddle assembly embodiment is illustrated. In this form, the paddles 60 and 62 differ from the previously described paddles 50 and 52 only in that the edge portions 60b and 62b are curved from the radially extending portions 60a and 62a. The effective angles of 30° and 60° are maintained and this form functions in exactly the same manner as that previously described. It should be noted that the length of the angled edge portions is determinative only of the volume of etchant delivered, the edge angle being the determining factor as to when the etchant is released.

In FIG. 6 a further modified form of paddle assembly is illustrated. This form comprises six paddles, 70-75, each of which includes radial portions, 70a-75a, secured to a collar 80 on shaft 82 such as by welding. The outer edge portions 70b-75b of the paddles are formed at various angles as indicated to produce the uniform etching action described above.

Specifically edge portions 70b, 71b and 72b are respectively formed at 23°, 30° and 37° to their paddles' radial portion. These paddles effectively carry out the function of the 30° paddle of the preferred embodiment. Similarly, edge portions 73b, 74b and 75b are angled respectively at 53°, 60°, and 67° to their paddles' radial portions, thus effectively carrying out the function of the 60° paddle of the preferred embodiment.

In operation, paddle assemblies such as shown in FIG. 6 operate in the same manner as described above, with the etchant delivered by the 23°, 30° and 37° paddles being counteracted by that delivered by the 53°, 60° and 67° paddles of adjoining assemblies.

A number of other combinations of paddles having variously angled edge portions may be employed within the scope of the invention. For example, four equally spaced paddles having 30°, 60°, 30°, and 60° edge portions. Another example is an assembly of four paddles of 25°, 35°, 55° and 65°. These examples are not meant to be exhaustive and the desired uniform etching effect can be obtained with variously angled blades in the ranges substantially of 23°-37° and 53°-67° provided a suitable counterbalance is maintained.

Manifestly, changes in details of construction can be effected by those skilled in the art without departing from the spirit and the scope of the invention as defined in and limited solely by the appended claims.

We claim:

1. In an etching machine having a tank adapted to contain an etching bath, means for supporting a photoengraving plate above the etching bath, a plurality of paddle assemblies rotatably disposed between the plate and the etching bath adapted to direct etchant from the etching bath against the photoengraving plate, and selectively variable means for rotating said paddle assemblies within a range of operating speeds, the improvement wherein each said paddle assembly comprises at least two paddles having outer edge portions adapted to pass through the etching bath, the paddle outer edge portions being angled with respect to the radial portion thereof in the direction of paddle rotation, and means on said paddles

2. The improvement as claimed in claim 1 wherein each said paddle assembly includes a first paddle having an outer edge portion disposed at an angle substantially within the range 23°-37°, and a second paddle having an outer edge portion disposed at an angle substantially within the range 53°-67°.

3. The improvement as claimed in claim 1 wherein said paddle assembly includes a first paddle having an outer edge portion disposed at a 30° angle, and a second paddle having an outer edge portion disposed at a 60° angle.

4. The improvement as claimed in claim 3 wherein said first and second paddles are in diametrically opposed relation on the paddle assembly.

5. In an etching machine having a tank adapted to contain an etching bath, means for maintaining the bath at a predetermined level, means for supporting a photoengraving plate above the etching bath in spaced parallel relation with the surface of the bath, means for providing planar movement of said photoengraving plate, a plurality of paddle assemblies having spaced parallel horizontal axes rotatably disposed between the plate and the etching bath and adapted to direct etchant from the etching bath against the photoengraving plate, and selectively variable means for rotating said paddle assemblies within a range of operating speeds, the improvement wherein each said paddle assembly comprises a plurality of paddles, each paddle including an inner radially extending portion and outer edge portion, the outer edge portions of the paddles of each assembly being variously angled with respect to the radially extending portions in the direction of rotation of the as-

sembly, a first paddle of each assembly having an edge portion disposed at an angle within the range 23°-37° to the radially extending portion, and a second paddle of each assembly having an edge portion disposed at an angle within the range 53°-67° to the radially extending portion whereby the variously angled paddles of the plurality of paddle assemblies cooperate to produce the equivalent effect of a substantially perpendicular direction of the etchant against the plate surface at any speed within the operating speed range.

10 5. The improvement as claimed in claim 5 wherein said first paddle of each assembly has an edge portion disposed at a 30° angle to the radially extending portion, and said second paddle has an edge portion disposed at a 60° angle to the radially extending portion.

15 6. The improvement as claimed in claim 5 wherein said first and said second paddles are in substantially diametrically opposed relation on the paddle assembly.

UNITED STATES PATENT OFFICE
CERTIFICATE OF CORRECTION

Patent No. 3,627,614 Dated December 14, 1971

Inventor(s) Louis E. Zeller and Robert J. Patasko

It is certified that error appears in the above-identified patent and that said Letters Patent are hereby corrected as shown below:

Column 4, line 66, after "paddles" insert --for producing the equivalent effect of a substantially perpendicular direction of the etchant against the plate surfaces upon rotation of the paddle assemblies at any speed within the operating speed range, said latter means comprising a substantially greater angle of one paddle edge portion with respect to its radial portion than of the other paddle edge portion.--.

Signed and sealed this 30th day of May 1972.
